US0D1039807S

(12) United States Design Patent (10) Patent No.: US D1,039,807 S
(45) Date of Patent: * Aug. 27, 2024

(54) SHOE

(71) Applicant: NIKE, Inc., Beaverton, OR (US)

(72) Inventor: Brenton Wehrmeyer, Portland, OR (US)

(73) Assignee: NIKE, Inc., Beaverton, OR (US)

() Term: 15 Years

(21) Appl. No.: 29/864,037

(22) Filed: May 5, 2022

(51) LOC (14) Cl. 02-04

(52) U.S. Cl.

USPC D2/947

(58) Field of Classification Search

USPC D2/896, 900, 902, 907, 946, 947, 948, D2/949, 950, 951, 952, 953, 954, 955, D2/956, 957, 958, 959, 960, 961, 964, D2/972, 973, 974, 976, 977

CPC A43B 3/244; A43B 3/246; A43B 5/00; A43B 5/06; A43B 5/10; A43B 13/125; A43B 13/127; A43B 13/12

See application file for complete search history.

(57) CLAIM

The ornamental design for a shoe, as shown and described.

DESCRIPTION

FIG. 1 is a side view of a shoe showing my new design; FIG. 2 is a rear perspective view thereof; FIG. 3 is a rear view thereof; FIG. 4 is an opposite side rear perspective view thereof; and, FIG. 5 is an opposite side view thereof. The broken lines depicting the remainder of the shoe form no part of the claimed design.

1 Claim, 5 Drawing Sheets
